UNITED STATES PATENT OFFICE.

DAVID FRANK, OF BROOKLYN, NEW YORK, ASSIGNOR OF ONE-HALF TO
JOHN TROUNSTINE, OF NEW YORK, N. Y.

DESIGN FOR AN END FRAME FOR BEDSTEADS.

SPECIFICATION forming part of Design No. 34,190, dated March 5, 1901.

Application filed February 9, 1901. Serial No. 46,739. Term of patent 7 years.

To all whom it may concern:

Be it known that I, DAVID FRANK, a citizen of the United States, residing at Brooklyn, Kings county, New York, have invented and 5 produced a new and original Design for an End Frame for Bedsteads, of which the following is a specification, reference being had to the accompanying drawing, forming a part thereof, and in which is represented a front 10 elevation of an end frame for bedsteads bearing and incorporating my design.

The leading features of my design consist of the form and ornamental configuration of the end frame, substantially as shown.

15 In the drawing, A A designate the corner-posts of the end frame, and B denotes the top rail, extending intermediate said corner-posts and with the same defining the exterior outline of the end frame. The upper portions of 20 the posts A A curve outward and then inward, as at C, where they merge into the top rail B,

which has the central curved section D, harmonizing with the curved portions C.

E indicates the usual lower horizontal rod or rail, between which and the upper ornamenteally-scrolled rods F F are the vertical rods G. The rods F F at their inner adjacent portions form the ornate scrolls H H within the field defined between the top rail B and the main portions of said rods F F, as 25 30 shown.

What I claim is—

The design for an end frame for bedsteads, substantially as shown and described.

Signed at Brooklyn, in the county of Kings 35 and State of New York, this 5th day of February, 1901.

DAVID FRANK.
